TOOTH GUARD AND JAW PROTECTOR

Domenico James Alfieri, Palo Alto, Calif.

Application December 6, 1954, Serial No. 473,388

5 Claims. (Cl. 128—136)

This invention relates to mouth pieces such as are generally used by athletes, boxers and the like for protecting their teeth, lips and jaws from injury by excessive blows or shocks.

Devices of this kind are generally accepted and widely used, there being various types and designs of mouth pieces all of which have the common characteristic of being inserted into the user's mouth to serve as a cushion between his upper and lower teeth.

Since each person is unique in that no two people have teeth of identical shape or spacing or within an identical arc or pattern, it will be apparent that in order to obtain a good fit each person would have to order a mouth piece to be custom made or fitted to this own jaw and tooth dimensions. This is a rather expensive process requiring that an impression be made in the same manner as required in the fitting and manufacture of denture plates. Moreover, the impression thus formed must be converted to a mold within which a rubber base substance is poured to form such a custom made mouth piece.

Attempts have been made to mass produce mouth pieces made of rubber but such mass produced devices are obviously without impressions of one's teeth and therefore a user must constantly keep his jaws closed to hold the mouth piece in place. This, of course is difficult for athletes and boxers because it is a known fact that during extreme physical exertion these people need more oxygen and as a result will breathe through the mouth and often gasp for air with their jaws widely opened. Consequently if the mouth piece is not secured they become gagged and might even swallow the mouth piece.

It is an object of the present invention to provide a mouth piece which can be mass produced and yet be susceptible to exact fitting to the user so as to adhere to the upper teeth. In connection with this broad concept, it is an object to provide a mouth piece having a mass produced primary material filled with a secondary material capable of receiving an impression of the user's upper teeth and gums. This object includes the advantage of providing a self-made impression on the part of the user and therefore enables the mass produced mouth piece of the present invention to adhere to the upper row of teeth thus overcoming gagging.

It is another object of this invention to provide a primary cup or body for a mouth piece in a fashion for bonding to a secondary material or impression receiving filler.

Another object is to provide a primary body of a mouth piece with a reinforcing for maintaining its shape.

These and other objects and advantages of the present invention will become apparent from a reading of the following description in the light of the accompanying drawings in which:

Fig. 1 is a side view of the mouth piece of the present invention illustrated in situ in a person's mouth.

Fig. 2 is an enlarged perspective view of the primary

2

cup or body of the mouth piece of Fig. 1 as seen from the back and above.

Fig. 3 is a front view of the mouth piece of Figs. 1 and 2.

5 Fig. 4 is a longitudinal section of the mouth piece of Fig. 1.

Fig. 5 is a vertical section of Fig. 4 taken substantially transversely along line 5—5 thereof.

10 Fig. 6 is a vertical section of Fig. 5 taken along line 6—6 thereof.

Fig. 7 is a perspective view complementary to that of Fig. 2 and showing a reinforcing member embedded in the primary cup or body therein illustrated.

15 In the drawings, the mouth piece is generally designated 10. It consists of a main or primary body 11 and a secondary material or filler 12. In addition to the foregoing, and if desired, the primary body 11 may include a reinforcing element or member 13.

20 The primary body 11 consists of a precast cup or retaining member 14 formed of a yieldable moldable material such as rubber or any other firm yet resilient shock absorbing substance which will lend itself to the purpose contemplated. Best results have been obtained by admixing latex rubber with strands of cellulose fibrous material which serve as a binder for this primary material.

25 It is intended that this primary body 11 be mass produced in stock sizes which vary only according to jaw dimensions. For example, for small, large or medium mouth sizes. In all other respects each device is identical in construction and has all of the attributes of the concept of the present disclosure.

30 The cup or retaining member 14 of the primary body 11 comprises a U-shaped diaphragm or separator 15 adapted to be disposed between the cusps of upper and lower teeth in a person's mouth to act as a separator therefor. The lower face 16 of the diaphragm 15 provides a relatively flat but yieldable surface adapted to rest upon the cusps of the lower teeth LT. The upper side of the diaphragm 15 likewise provides a relatively flat surface 17. In addition to the foregoing, the retaining member or cup 14 includes inner and outer retaining walls 18 and 19, respectively, throughout the 40 entire U shape of the primary body 11. These inner and outer retaining walls 18 and 19 are formed integrally with the main body 11 and include fore and aft walls 19'—18' respectively at the bight of the U-shaped diaphragm 15.

45 Therefore retaining wall 18' includes an overhanging lip 20 which extends downwardly beyond the plane of the diaphragm 15 so as to partially overlie the crown portions of the lower front teeth of the user. This lip 20 circumscribes only part of the lower teeth and is particularly intended to protect the lips of the user from injury by blows against the incisors and canines or eye teeth. The lip 20 has a further purpose of being engaged by the frontal lower teeth to prevent backward shifting of the entire mouth piece within the mouth of the user.

50 Referring now to Figs. 4, 5 and 6, it will be seen that the inner and outer retaining walls 18—19 extending upwardly from the diaphragm 15 cooperate with the latter in forming a trough-like receptacle 14 throughout the extent of the U-shaped main or primary body 11.

55 In this connection, the upper edge 22 of both inner and outer walls 18—19 are provided with an inwardly extending bead 23. The inner faces of the walls 18—19 as well as the upper face 17 of the diaphragm 15 also have 60 projections 24 formed thereon. These projections are

65 preferably convex tabs disposed in staggered relation with respect to each other throughout the inner confines of the trough-like receptacle 14.

The secondary material or filler 12 consists of a rubber base material which is fusible at a low temperature as distinguished from the primary material which is tough and resilient having an affinity to withstand cutting from the teeth and to always return to its normal shape and thickness even after undue pressure. In contrast with the primary material the secondary material 12 will soften at a temperature slightly higher than body or mouth temperature. As a result of this characteristic the secondary material is capable of receiving an impression when heated to about 112° F. This is usually done by submerging the material into a glass of hot water for a sufficient time to soften the material.

The secondary material 12 is first placed within the trough-like receptacle 14 filling the same up to the inwardly extending beads 23 which form a rim around the receptacle. The secondary material is first heated to approximately 112° F. before being placed in the receptacle 14 and therefore becomes pliable and will mold itself to the shape of the U-shaped receptacle as well as the many fins or tabs 24 projecting inwardly from the walls and bottom thereof. In this manner the secondary material 12 is adequately anchored and will adhere to the inner walls of the receptacle provided in the primary or main body 11 of the mouth piece. Moreover, the rim around the receptacle 14 formed by the inwardly extending beads 23 serve to maintain the secondary material 12 within the receptacle. This bead 23 being continuous around the entire upper edge of either retaining wall 18-19 serves to maintain the upper edges of these walls in true form so that they will not curl out and break away from the secondary material.

From the foregoing it will be appreciated that the mouth piece 10 is presented in a form ready for use, i. e., without any tooth impressions in the secondary material 12. However, the purchaser is instructed to dip the entire mouth piece 10 into warm water (slightly above mouth temperature) for a predetermined lapse of time. This will render the secondary material soft enough to receive impressions. The user then inserts the entire unit 10 into his mouth in proper position between upper and lower arches of his teeth. In this position the secondary material 12 is uppermost, i. e., in register with the teeth in the upper jaw. He then bites down upon the mouth piece 10, while it is still at a temperature above body heat. Thus he makes an impression into the secondary material 12 corresponding exactly to his upper teeth.

After the secondary material 12, with impression therein, cools even to normal body or mouth temperature (98.6° F.) the secondary material 12 will set up and remain in the exact shape of the upper row of teeth. Thus a perfect fit is obtained and adherence of the mouth piece 10 to the upper jaw or row of teeth therein is always assured.

In addition to the foregoing it will be appreciated that any change in the wearer's denture, i. e., his tooth arrangement or structure, can be readily compensated for by the mouth piece of the present invention. For example, should the owner of the mouth piece have a tooth extracted he need only dip the mouth piece in a glass of hot water to soften up the secondary material, knead it with his fingers and then insert it into his mouth and bite down upon it to make a new impression corresponding to his new or changed tooth structure.

Insofar as the present invention is concerned its broader aspects, as hereinbefore explained, will afford good mouth and tooth protection. The main or primary body 11 being made of a rubber base material may have a tendency to flex or bend if it is not stiff enough to withstand such flexing or bending. In order to counteract this tendency the reinforcing member 13 (Fig. 7) is a relatively stiff structural member so formed as to be embedded in the primary body 11 at the time of molding or casting of the latter.

In connection with the foregoing, the reinforcing member 13 may be formed of metal or preferably of a hard, relatively stiff plastic material. In either event the reinforcing element 13 is of a U shape conforming to the arch or U shape of the primary body 11. It has a horizontal flat portion 30 of a width which will wholly confine it within the diaphragm 15 of the main body 11.

At the end portions of the legs of the U-shaped reinforcing member 13 there are provided upturned inner and outer side flanges 38-39, respectively, so disposed as to be embedded in the inner and outer walls 18-19 of the main body 11. Thus these relatively thin upstanding walls 18-19 of the main body or trough-like receptacle 14 are rigidified and prevented from spreading, i. e., being forced away from each other, when pressure is applied to the secondary material 12 between them during formation of tooth impressions into the secondary material as hereinbefore explained.

In order to assure bonding of the rubber base material of the primary body 11 to the reinforcing member 13 the latter is provided with perforations 40 throughout its flat or horizontal portion 30 as well as its upstanding flanges 38-39. Thus when the main or primary body 11 is cast or molded the rubber base material thereof flows through the perforations 40 in the well known manner to secure the reinforcing member 13 within the main body 11.

Having thus described my improved mouth piece in specific detail it will be apparent that it is susceptible to alteration, modification, and/or variation without departing from the spirit of my invention. I therefore desire to avail myself of such alterations, modifications and variations as fairly come within the purview of the appended claims.

What I claim as new and desire to protect by Letters Patent is:

1. In a tooth guard and jaw protector adapted to fit and worn in a person's mouth between the teeth of the upper and lower jaws thereof, a main body of primary material having an affinity of maintaining its own shape comprising a U-shaped diaphragm adapted to be disposed between the teeth of the upper and lower jaws of the wearer of the protector, inner and outer retaining walls on the upper face of said diaphragm to provide a trough-like receptacle thereon, a plurality of integral tabs extending inwardly from said diaphragm and inner and outer retaining walls and a filler in said trough-like receptacle consisting of a secondary material having an affinity when heated beyond mouth temperature to anchor itself to said tabs and to receive the impression of the teeth in the upper jaw of the wearer when he bites down upon said tooth guard and jaw protector while said secondary material is yet in a heated, pliable state.

2. In a tooth guard and jaw protector adapted to fit in a person's mouth between the teeth of the upper and lower jaws thereof, a main body consisting of a rubber base primary material having an affinity of maintaining its own shape comprising a U-shaped diaphragm adapted to be disposed between the teeth of the upper and lower jaws, integral inner and outer retaining walls on the upper

face of said diaphragm to provide a trough-like receptacle thereon, a filler in said trough-like receptacle consisting of a secondary material having an affinity when heated beyond mouth temperature to receive an impression when pressure is applied thereto, said inner and outer retaining walls having a continuous inturned bead formed thereon adjacent their upper edges for securing said secondary material within said trough-like receptacle, and a plurality of tabs formed integrally with said main body and promiscuously interspersed on the upper face of said diaphragm and the inner face of said inner and outer retaining walls for anchoring said secondary material thereto.

3. In a tooth guard and jaw protector of the type including a U-shaped body member adapted to fit between the upper and lower teeth in a person's mouth and having a trough-like receptacle on its upper face in which

75

an impression receiving material is confined and adapted when heated to slightly above mouth temperature for receiving the impression of the teeth in the upper jaw of the user, a plurality of staggered tabs formed integrally with said body member within said trough-like receptacle for anchoring said impression receiving material therein.

4. In a tooth guard and jaw protector of the type including a U-shaped base rubber member adapted to fit between the upper and lower teeth in a person's mouth and having inner and outer retaining walls around the upper face thereof to provide a trough-like receptacle for confining a secondary material adapted when heated to slightly above mouth temperature to receive an impression of the teeth in the upper jaw of the user, means for counteracting the tendency of said base rubber member to flex or bend comprising a U-shaped reinforcing member embedded in the floor portion of said trough-like receptacle and having upturned inner and outer flanges embedded in said inner and outer retaining walls respectively thereof.

5. In a tooth guard and jaw protector of the type including a U-shaped base rubber member adapted to fit between the upper and lower teeth in a person's mouth

and having inner and outer retaining walls around the upper face thereof to provide a trough-like receptacle for confining a secondary material adapted when heated to slightly above mouth temperature to receive an impression of the teeth in the upper jaw of the user, means for counteracting the tendency of said base rubber member to flex or bend comprising a U-shaped reinforcing member embedded in the floor portion of said trough-like receptacle and having upturned inner and outer flanges embedded in said inner and outer retaining walls respectively thereof, and a plurality of tabs formed on the inside faces of said trough-like receptacle integrally with said base rubber member for anchoring said secondary material therein.
